[57] ABSTRACT

A keyboard type electronic musical instrument, having a group of twelve keys per octave for playing the even tempered scale, is adapted to sound the quarter tone between two notes of the even tempered scale when the keys corresponding to said two notes are simultaneously operated. The instrument employs a voltage controlled oscillator, a voltage source having output voltages proportional to the frequencies of the notes of the scale, a group of key operated switches and series resistors for selectively connecting the oscillator to the voltage source. The resistors of operated switches form a voltage divider when two keys are simultaneously operated and a voltage equal to the average of the converted voltages is applied to the oscillator to produce the intermediate tone.

FIG.2

FIG.1

KEYBOARD TYPE ELECTRONIC MUSICAL INSTRUMENT

This is a continuation of application, Ser. No. 121,831, filed Mar. 8, 1971, now abandoned.

BACKGROUND OF THE INVENTION

1. Field of the Invention

This invention relates to a keyboard type electronic musical instrument which is provided with a plurality of keys and adapted to provide a predetermined musical scale by sequential depression of the keys and the invention is of particular utility when employed in such a keyboard type electronic musical instrument designed to provide the dodecaphonic scale.

2. Description of the Prior Art

With conventional electronic musical instruments of the type above mentioned, semitones can be produced but quarter tones cannot be produced. Therefore, the prior art electronic musical instruments cannot raise the performance effect such as those obtainable with, for example, a guitar, a saxophone, a clarinet and the like.

SUMMARY OF THE INVENTION

Accordingly, the present invention has for its object to provide a keyboard type electronic musical instrument which is designed to produce quarter tones without requiring any special keys therefor. In accordance with this invention a quarter tone can be produced by simultaneous depression of two adjacent keys.

BRIEF DESCRIPTION OF THE DRAWING

FIG. 1 is a system diagram showing one example of a keyboard type electronic musical instrument of this invention; and

FIG. 2 is a graph showing a voltage-frequency characteristic, for explaining the operation of the keyboard type musical instrument exemplified in FIG. 1.

DESCRIPTION OF THE PREFERRED EMBODIMENT

In FIG. 1 reference numeral 1 indicates generally one portion of a usual dodecaphonic keyboard, which is shown to consist of keys K₁ to K₁₂ of one octave for the sake of brevity and are arranged in order of "C," "C[#] (D[#])," "D," . . . as usual.

Reference numeral 2 designates generally a switch array which is provided corresponding to the keyboard 1 and includes switches S₁ to S₁₂ respectively associated with the keys K₁ to K₁₂ and closed by the depression of the respective keys K₁ to K₁₂.

Reference numeral 3 identifies a DC power source circuit, in which resistors R₁ to R₁₂ are respectively connected in series to a power source 4 through a resistor R₀ to derive DC voltages V₁ to V₁₂ at connection points P₁ to P₁₂ between adjacent resistors respectively. The connection points P₁ to P₁₂ are respectively connected to the switches S₁ to S₁₂ through resistors r₁ to r₁₂ of the same relatively high resistance value.

Reference numeral 5 indicates a voltage-controlled oscillator adapted to produce a tone signal of a fundamental frequency corresponding to an input voltage. The oscillator 5 is connected at input side to the other ends of the switches S₁ to S₁₂ and connected at output side to a speaker system 7 through an amplifier 6.

With such an arrangement as above described, depression of the keys K₁ to K₁₂ respectively applies the

voltages V₁ to V₁₂ to the voltage controlled oscillator 5 to derive therefrom tone signals of fundamental frequencies f₁ to f₁₂ corresponding to the voltages and the resulting tone signals are supplied through the amplifier 6 to the speaker 7 to be thereby reproduced.

Accordingly, if the values of the resistors R₀ to R₁₂ in the power source circuit 3 and consequently the values of the voltages V₁ to V₁₂ are selected so that the fundamental frequencies f₁, f₂, . . . may respectively be equal to those of "C," "C[#] (D[#])," "D" . . . forming the dodecaphonic musical scale, the relationships of the voltages V₁, V₂, . . . with the frequencies f₁, f₂, . . . are such as shown in FIG. 2, in which the values of the voltages V₁, V₂, . . . become sequentially higher in their order to provide the frequencies f₁, f₂, . . . corresponding thereto. Therefore, selective depression of any one of the keys K₁ to K₁₂ produces a particular semitone of the fundamental frequency of the depressed key, thus achieving keyboard performance in the same manner as that of a usual keyboard type monotony electronic musical instrument.

However, when the keys for example, K₁ and K₂ are simultaneously depressed, the voltage-controlled oscillator 5 is supplied with a voltage which is substantially one half of the sum of the voltages V₁ and V₂ or (V₁ + V₂)/2 so that a tone signal of a fundamental frequency about (f₁ + f₂)/2 is produced by the oscillator 5. Since the frequencies f₁ and f₂ are equal to those of "C" and "C[#] (D[#])," simultaneous depression of the keys K₁ and K₂ provides a quarter tone which is intermediate between those of "C" and "C[#] (D[#])." Further, simultaneous depression of the keys, for example, K₂ and K₃ similarly produce a quarter tone between "C[#]" and "D."

The following will describe concrete numerical values of the circuit elements of this invention.

The voltage-controlled oscillator 5 is an oscillator which has a linear voltage-frequency characteristic and produces a frequency 100 c/s when supplied with 1 volt. The power source 4 of the power source circuit 3 has a voltage of 4.9388 volts. The resistance values of the resistors R₀ to R₁₂ are as follows:

R ₀ :	2616.3 ohms
R ₁ :	155.5 ohms
R ₂ :	164.8 ohms
R ₃ :	174.7 ohms
R ₄ :	185.0 ohms
R ₅ :	196.0 ohms
R ₆ :	207.6 ohms
R ₇ :	220.1 ohms
R ₈ :	233.0 ohms
R ₉ :	247.0 ohms
R ₁₀ :	261.6 ohms
R ₁₁ :	277.2 ohms
R ₁₂ :	0 ohms

The resistance values of the resistors r₁ to r₁₂ are respectively 10 kilohms.

With such resistance values of the resistors R₀ to R₁₂, a current of 1 mA flows from the power source 4 to the series circuit of the resistors R₀ to R₁₂, thereby to derive the following voltages V₁ to V₁₂ at the connection points P₁ to P₁₂:

V ₁ :	2.6163 volts
V ₂ :	2.7718 volts
V ₃ :	2.9366 volts
V ₄ :	3.1113 volts
V ₅ :	3.2963 volts

V_6 : 3.4923 volts
 V_7 : 3.6999 volts
 V_8 : 3.9200 volts
 V_9 : 4.1530 volts
 V_{10} : 4.4000 volts
 V_{11} : 4.6616 volts
 V_{12} : 4.9388 volts

Since the resistance values of the resistors r_1 to r_{12} are large compared to the resistance of the resistors R_0 to R_{12} , so that when each of the switches S_1 to S_{12} is closed each of the aforementioned voltages is supplied to the voltage-controlled oscillator 5. Accordingly, depression of each of the keys K_1 to K_{12} derives each of the following fundamental frequencies from the oscillator 5.

K_1 : 261.63 c/s
 K_2 : 277.18 c/s
 K_3 : 293.66 c/s
 K_4 : 311.13 c/s
 K_5 : 329.63 c/s
 K_6 : 349.23 c/s
 K_7 : 369.99 c/s
 K_8 : 392.00 c/s
 K_9 : 415.30 c/s
 K_{10} : 440.00 c/s
 K_{11} : 466.16 c/s
 K_{12} : 493.88 c/s

These fundamental frequencies correspond to those of "C", "C (D)", "D", . . . of the dodecaphonic scale.

Further, when the switches, for example, S_2 and S_3 are concurrently closed, a voltage, which is substantially $(V_2 + V_3)/2 = (2.7718 + 2.9366 V)/2$, is applied to the voltage-controlled oscillator 5. As a result of this, the oscillator 5 produces a frequency 285.42 c/s corresponding to a quarter tone which is intermediate between "C#" and "D."

With the present invention, a quarter tone can be produced by simultaneous depression of adjacent keys without requiring any special keys therefor. Therefore, this invention provides a keyboard type electronic musical instrument of high performance effect.

It will be apparent that many modifications and variations may be effected without departing from the scope of the novel concepts of this invention.

I claim as my invention

- 10 1. In a keyboard electronic musical instrument comprising a keyboard provided with at least one group of twelve keys for one octave, in combination, an electrical power source having a plurality of output points delivering a plurality of output voltages proportional to the frequencies of the tones corresponding to said keys, a switch for each key operated by the key, a resistor connected in series with each switch, the resistances of said resistors being substantially equal to each other and large compared to the impedance of the power source and a voltage controlled oscillator having a control voltage input terminal, each switch and series connected resistor being separately connected between said control voltage input terminal and the power source terminal corresponding to the switch and associated key, whereby actuation of the keys individually applies corresponding voltages to the voltage controlled oscillator and simultaneous actuation of two keys applies a voltage intermediate the voltages of the switch connected points to the voltage controlled oscillator.
- 15 2. A circuit for a keyboard type electronic musical instrument according to claim 1 in which said power source includes a plurality of resistors connected in series with the junctions between the resistors connected to said output points.
